GYPSUM TIMBER

Albert J. Meier, St. Louis, Mo., assignor, by mesne assignments, to Rockwood Gypsum Corporation of America, St. Louis, Mo., a corporation of Nevada

Application April 16, 1923, Serial No. 632,425

21 Claims.

(Cl. 72—66)

This invention relates to building timbers, and more particularly to such timbers artificially manufactured by casting out of lithic material.

In accordance with the present invention the material used for the manufacture of this timber is gypsum in the calcined form which, after being mixed with water, may be poured into molds in a manner similar to the manufacture of reenforced concrete structures or the like. Gypsum in this or similar forms has been used for casting various shapes, such as small statuary and ornaments of various kinds. This material is also cheap and easy to handle. It is not strong enough, however, to lend itself readily to structural purposes in the same way as cement concrete which may be reinforced by steel in those parts which are subjected to tensile stresses.

One of the objects of this invention is to provide a building timber of cast gypsum which may be effectively used in building construction.

Another object of this invention is to provide a timber of cast gypsum, having incorporated therein a suitable binder, such as bagasse.

Another object is to provide a timber of cast gypsum, which is adapted to form, with suitable means, a load bearing element.

Another object of this invention is to provide a timber of cast gypsum which is arranged to receive concrete in order to form a beam.

Further objects will appear from the detail description taken in connection with the accompanying drawings, in which:

Figure 1 is a perspective view illustrating a timber embodying this invention;

Figure 2 is an enlarged end view of Figure 1;

Figure 3 is a partial cross-sectional view of a floor built of these timbers;

Figure 4 and 5 are perspective views illustrating other modified forms of the timber embodying this invention;

Figures 6, 7, 8, 9 and 10 illustrate still further embodiments of this invention; and

Figure 11 is a perspective view showing the general plan of wall and floor construction in accordance with this invention.

While the complete building structure is described in this specification, the wall structure per se is not claimed herein but is claimed in my co-pending application Serial No. 142,636 filed May 14, 1937, which is a division of this application.

In accordance with this invention, a timber is provided, formed of cast gypsum. In accordance with this invention, a hollow building structure timber of cast gypsum is provided, which is char-

acterized by the feature that it has a length which is large compared to its transverse dimension, but is of sufficient rigidity and strength to carry a load when supported at its ends. It, therefore, distinguishes from building blocks and the like, which are not timbers. This timber preferably has incorporated therein and with the gypsum, a suitable binder, such as bagasse, although other fibrous binders, such as cut rope or wood chips may be used. The timber may also be suitably reinforced with rods, bars or other elements such as are employed in the reinforcement of concrete generally.

In practice, where a binder, such as bagasse, is used, the binder, in the proportion of 5% to 10% of the total mass, and in shredded form and short lengths of the size of hogs' hair, is mixed with the water in order to form a thick soupy mixture. To this is then added the calcined gypsum, and the whole is cast in a suitable form or mold.

The timber when used for a wall is formed to provide one or more cavities or cells therealong, and it may be formed to provide a tongue and groove therealong. The timber may also be provided with channels or other means in order to provide a plaster-receiving and retaining face. When erected in a wall, certain of the cavities may be filled with concrete, suitably reinforced, in order to provide supporting means for the wall.

Where the timber is to form a floor or other load bearing part, it is constructed to receive concrete in order to provide a beam. Accordingly the timber is formed to provide a channel adapted to receive concrete, suitably reinforced; and in order to provide for shipment the timber has a series of cavities therealong, the wall of one of which may be broken open to provide the channel.

Referring to the accompanying drawings and more particularly to Figures 1, 2 and 3, Figure 1 shows a general view of a building timber embodying this invention, the particular one shown being designed to form a floor timber. It is cast in a generally rectangular hollow form, the body 1 of the timber having three longitudinal cavities 2 extending throughout its length, a center cavity 2 and lateral cavities 3. Metal reenforcing elements 4 and 5 may, if desired, be imbedded in the walls of the timber as illustrated in Figures 1 and 2. These reenforcing elements may be of any desired form best suited for the purpose. Longitudinal members 5 may be placed at the corners and transverse members 4 may be imbedded in the walls. It will be noted that the upper wall 6 of the center cavity 2 is not only

formed without reenforcement, but is made thinner than the other walls. This is for the purpose of rendering the wall 6 friable so that it may be broken out for a purpose which will be presently explained.

Figure 3 illustrates a floor construction using these timbers. The timbers 1 are assembled in adjoining relation as illustrated, being suitably supported by means not shown in this view. After assembling the units, the walls 6 of each will be broken out throughout its length so that the center cavity 2 of each unit is left open at the top. This cavity now provides a form or channel in which a reenforced concrete beam may be cast. Reenforcing bars 7 may be placed in the cavity and the concrete filling 8 may then be poured in the usual way. If desired, suitable strips 9 may be imbedded in the concrete filling to provide nailing strips for the floor 10. It will be noted that the side walls of the cavity 2 slope toward each other toward the top. The concrete beam which is cast in this cavity will, therefore, have a dove tailed shape adapted to securely interlock the same with the timbers 1.

The wall timbers 11 may be formed as illustrated in Figures 4 to 10 inclusive. These are cast in a substantially rectangular form in cross-section having a cavity 12 as illustrated in Figure 4 or a number of cavities as illustrated in Figure 5, according to the service for which the unit is intended. One edge of the timber is provided with a tongue 13 and the opposite edge with a groove 14 so that the adjoining timbers may be interlocked by engagement of tongues and grooves in a well known manner. One or both faces of the timber may be provided with transverse grooves 15 for the engagement of plaster or other suitable facing to be applied to the wall as a finish.

In casting these timbers, a suitable paper facing 16 may be placed in the mold so that the finished timber will be provided with a reenforcing facing of paper, fabric or other fibrous material which will not only assist in reenforcing the surface but will also provide a surface to which materials used for finishing will adhere. It is, of course, immaterial whether the paper be inserted in the mold and attached to the surface during the casting operation or the casting be completed first and the facing applied afterward. Figure 7 shows the facing 16 applied to two opposite sides of the timber. In Figure 8 the facing is carried completely around the timber and in Figure 9 a facing 17 is also applied to the interior surface of the cavity 12.

In Figure 11 is illustrated a method of constructing the wall in accordance with this invention. As will be seen the timbers 11 are placed up-right on a suitable foundation and in adjoining relation with one another, the tongues of one timber engaging the grooves in the adjoining one; in practice the tongues and grooves will be so smooth as to form a sufficiently tight joint, however, if desired a layer of mortar may be provided to complete the joint. These timbers are in practice long enough to complete the wall between two floors; however, shorter lengths may be placed, one upon the other in vertical sections so that the cavities of all those in a vertical stack will register with one another. When a suitable height of wall has been built up, certain selected cavities have inserted therein one or more reenforcing members 18 which may be steel rods such as are ordinarily used in reenforced concrete constructions. When these reenforcing

members have been suitably positioned in the cavities, these cavities are filled with concrete so as to form columns adapted to provide supports for the floors and also to stiffen the wall structure.

When the wall has been built any desired facing may be applied to the outer surface thereof.

The construction of a building in accordance with this invention is illustrated in Figure 11. In this construction the walls are first erected by setting up timbers 11 in adjoining relation, as previously described, on a suitable foundation. When a sufficient height of wall has been built up, reenforcements 18 are inserted and the corresponding cavities filled with concrete as previously described. This provides a series of reenforced concrete columns at regular intervals along the wall. The floors may then be laid on by placing timbers 1 of the type shown in Figures 1 and 2 upon the walls so that their ends are supported by the up-right timbers 11. When these floor timbers have been put in place the friable partitions 6 are broken out and reenforcements 7 set in place. If desired reenforcing members may also be arranged lengthwise along the walls over the tops of the up-right timbers 11. These are shown at 33. When all reenforcing rods have been set in place the cavities in the timbers 11 and 1 which are not to be filled have their openings suitably closed after which concrete may be poured into the channels 26 and 30 also into the spaces between the ends of the floor timbers 1 and over the tops of the wall timbers 11, suitable forms in the shape of boards 30 having been first provided so as to retain the concrete in shape along the top of a wall. This filling of concrete will thus provide a series of reenforced concrete beams 31 bridging from wall to wall and supporting the timbers 1. The ends of these beams are connected by means of the concrete filling along the border 32 with the columns 40 formed by the fillings 23. It will be noted that the border 32 provides a reenforced concrete beam running along the top of each wall and joining the columns 23. The floor beams 31, also of reenforced concrete, are connected at their ends 45 with the columns through these beams along the top of the wall. It will thus be evident that a strong and rigid frame-work of reenforced concrete is provided which supports the wall timbers 11 and the floor timbers 1.

Succeeding stories may be built one upon the other by the same method, each succeeding story serving as a foundation for the one above it.

It will be noted that this invention provides a novel and economical method of building construction. Hollow lithic timbers are provided for both wall and floor construction. In the wall timbers cavities are provided within which reenforced concrete columns may be formed. In the floor timbers suitable cavities are also provided wherein reenforced concrete beams may be cast. By the method of construction described the columns and beams are connected by a reenforced concrete beam along the wall so that a strong and rigid structural frame is provided. The wall and floor structures are formed by building into this frame the timbers as described herein. Thus a strong and rigid shell is provided which is of the nature of the hollow tile construction so as to provide suitable heat insulating qualities and which also lends itself to the application of various forms of surface dressing for decorative and other purposes.

It is obvious that various changes may be made in details of construction without departing from

the spirit of this invention; it is, therefore, to be understood that this invention is not to be limited to the specific details shown and described.

Having thus described the invention, what is claimed is:

1. A self-supporting building structure timber of cast gypsum and of general rectangular hollow cross-section, characterized by the feature that it has a length which is large compared to its greatest transverse dimension but is of sufficient rigidity and strength to stand when supported at its ends, said timber being constructed to receive concrete for interlocking therewith and for interlocking and anchoring the timber with its supports.

2. A self-supporting building structure timber of cast gypsum having a series of cavities therewith formed by an internal web and lateral walls along and integral with the timber body, characterized by the feature that it has a length which is large compared to its greatest transverse dimension but is of sufficient rigidity and strength to stand when supported at its ends, said timber being constructed to receive concrete for interlocking therewith and for interlocking and anchoring the timber with its supports.

3. A self-supporting building structure timber of cast gypsum having a series of cavities therewith formed by internal webs and lateral walls along and integral with the timber body, characterized by the feature that it has a length which is large compared to its greatest transverse dimension but is of sufficient rigidity and strength to stand when supported at its ends, said timber being constructed to receive concrete for interlocking therewith and for interlocking and anchoring the timber with its supports.

4. A self-supporting building structure timber of cast gypsum whose length is large compared to its greatest transverse dimension and having a series of cavities therewith formed by lateral walls and an intermediate web, said timber being constructed to receive concrete for interlocking therewith and for interlocking and anchoring the timber with its supports.

5. A building structure comprising supports spaced to provide an extended span, and a building structure unit of gypsum having a length which is large compared to its greatest transverse dimension and adapted to span said supports, said unit being constructed to receive concrete for interlocking therewith and for interlocking and anchoring the unit with said supports.

6. A building structure comprising supports spaced to provide an extended span, and a building structure unit of gypsum having a length which is large compared to its greatest transverse dimension and adapted to span said supports, said unit having means for receiving and interlocking with concrete to provide an element structurally connecting said supports and for supporting said unit therewith.

7. A building structure comprising supports spaced to provide an extended span, and a building structure unit of gypsum having a length which is large compared to its greatest transverse dimension and adapted to span said supports, said unit being recessed therewith to provide a form adapted to receive concrete in order to form an element structurally connecting said supports and for supporting said unit.

8. A building structure comprising walls spaced to provide an extended span, building structure units of gypsum each of a length to span said walls, said units having recesses therewith and

from wall to wall, and concrete beams formed within said recesses and spanning from wall to wall.

9. In a building structure in which the supports are spaced to form an extended span which are connected by concrete columns or beams, a building structure unit of gypsum having a length which is large compared to its greatest transverse dimension and adapted to span the supports, said unit being recessed therewith to provide a form adapted to receive concrete in order to form an element structurally connecting said supports and for supporting said unit.

10. In the art of erecting building structures the walls or floors of which are composed of gypsum units and in which the structure is reinforced by concrete within and along some of the units to provide columns or beams, the process comprising placing a gypsum unit of a length which is large compared to its greatest transverse dimension and which has a recess therewith, in position to span the supports, and placing the concrete within the recess and to connect with the supports.

11. In the art of erecting floors, the process comprising, placing a series of hollow timbers of cast gypsum in adjoining relation, breaking open certain of the cavities to form channels, placing reinforcing elements to extend along said channels, and filling the channels with concrete to be supported by said timbers until it sets in order to provide beams.

12. In the art of erecting floors, the process comprising, casting hollow gypsum timbers, placing a series of such timbers in adjoining relation, breaking open certain of the cavities to form channels, placing reinforcing elements to extend along said channels, and filling the channels with concrete to be supported by said timbers until it sets in order to provide beams extending along said timbers adapted to support the same.

13. In the art of erecting floors, the process comprising, casting gypsum to form timbers each with a series of cavities therewith, placing a series of such timbers in adjoining relation, breaking open certain of the cavities to form channels, placing reinforcing elements to extend along said channels, and filling the channels with concrete to be supported by said timbers until it sets in order to provide beams extending along said timbers adapted to support the same.

14. A floor structure timber of cast gypsum characterized by the features, that it has a length which is large compared to its greatest transverse dimension, that a cavity extends therewith and is closed by a frangible top wall having weakened portions to be broken out after the timber is placed in the structure so as to provide a channel open at its ends adapted to receive concrete to form a supporting beam interlocking with its end supports, and that said timber has sufficient strength and rigidity to support the concrete in said cavity until it sets.

15. In the art of erecting floors, the process comprising, placing a series of elongated hollow timbers on spaced supports to form a floor, each to span the space between supports, and in adjoining relation with each other; breaking open cavities along certain timbers, placing reinforcing elements along those cavities, and filling those cavities with concrete in such a manner as to interlock with those timbers so as to cause those timbers to support the concrete filling until it sets whereby to form a concrete beam supporting said timbers.

16. A building structure comprising, a series of hollow gypsum timbers placed in adjoining relation to form a wall, a series of hollow gypsum timbers placed in adjoining relation to form a 5 floor, certain of the wall cavities being filled with concrete to provide supports, and certain of said floor cavities being channeled and filled with concrete to provide beams.
17. A building structure comprising, a series 10 of hollow gypsum timbers placed in adjoining relation to form a wall, a series of hollow gypsum timbers placed in adjoining relation to form a floor, certain of the wall cavities being filled with concrete to provide supports, certain of 15 said floor cavities being channeled and filled with concrete to provide beams, and said supports and said beams being connected by concrete.
18. A building structure, comprising, a series 20 of precast hollow gypsum timbers of a continuous length to span from floor to ceiling placed in adjoining relation to form a wall, a series of precast hollow gypsum floor timbers, of a continuous length to span the space between 25 supports, resting on said wall, and a concrete interlock between said wall and said floor timbers.
19. A building structure, comprising, a series 30 of precast hollow gypsum timbers of a continuous length to span from floor to ceiling placed in adjoining relation to form a wall, certain of said timbers being filled with concrete to provide reinforcing columns in said wall, a series of precast hollow gypsum floor timbers, of a con-
- tinuous length to span the space between supports, resting on said wall, and a concrete interlock between said wall and said floor timbers.
20. A building structure, comprising, a series 5 of precast hollow gypsum timbers of a continuous length to span from floor to ceiling placed in adjoining relation to form a wall, certain of 10 said timbers being filled with concrete to provide reinforcing columns in said wall, a series of precast hollow gypsum floor timbers, of a continuous length to span the space between supports, resting on said wall, certain of 15 said floor timbers having cavities extending therealong and filled with concrete to provide reinforcing floor beams interlocked with said wall, and a concrete interlock between said wall and said floor timbers.
21. A building structure, comprising, a series 20 of precast hollow gypsum timbers of a continuous length to span from floor to ceiling placed in adjoining relation to form a wall, certain of 25 said timbers being filled with concrete to provide reinforcing columns in said wall, a series of precast hollow gypsum floor timbers, of a continuous length to span the space between supports, resting on said wall, certain of 30 said floor timbers having cavities extending therealong and filled with concrete to provide reinforcing floor beams interlocked with said wall, and a concrete interlock between said wall and said floor timbers joining said columns and said beams into a unitary frame.

ALBERT J. MEIER.

CERTIFICATE OF CORRECTION.

Patent No. 2,087,522.

July 20, 1937.

ALBERT J. MEIER.

It is hereby certified that error appears in the printed specification of the above numbered patent requiring correction as follows: Page 1, first column, line 38, for "Figure" read Figures; line 39, strike out the word "modified"; and second column, line 46, after the comma insert the word and comma namely.; page 3, second column, line 8, claim 9, for "larged" read large; and that the said Letters Patent should be read with these corrections therein that the same may conform to the record of the case in the Patent Office.

Signed and sealed this 5th day of October, A. D. 1937.

Henry Van Arsdale

(Seal)

Acting Commissioner of Patents.
